1

This invention relates to a mixing circuit arrangement in which the incoming oscillations are supplied in push-pull arrangement and the local oscillations in single phase (in the same phase) to the input electrodes of two discharge systems each of which comprises at least one cathode, one input electrode and one output electrode.

For an understanding of the invention reference is had to the following detailed description thereof to be read in conjunction with the accompanying drawing wherein:

Fig. 1 is a schematic circuit diagram of a prior art push-pull mixing system.

Fig. 2 and 3 are substitution diagrams for the input circuit of the system in Fig. 1.

Fig. 4 is a schematic circuit diagram of a first preferred embodiment of a mixing system in accordance with the present invention.

Fig. 5 is a schematic circuit diagram of a second preferred embodiment of the invention, and

Fig. 6 is a schematic circuit diagram of a third preferred embodiment of the invention.

Fig. 1 of the accompanying drawing represents a mixing circuit of this kind, which forms part of a superheterodyne receiver for short waves. The oscillations captured by a dipole antenna D', D'' are inductively transmitted through an antenna coupling coil L₀ to an input resonant circuit consisting of two inductance coils L_{1'} and L_{1''} and a tuning condenser C₁ and being connected in push-pull between the control-grids of two mixing triodes T' and T''. The parasitic capacities between the inductance coils L_{1'} and L_{1''} respectively and the antenna coupling coil L₀ are represented by C_{0'} and C_{0''} respectively. The connecting point of coils L_{1'} and L_{1''} is earthed through a condenser C₂ and connected through a resistance R₁ to a supply (not represented) by which the control-grids of the triodes T' and T'' are suitably biased. The input capacities of the triodes T' and T'' are denoted by C_{3'} and C_{3''} respectively.

The cathodes of the triodes T' and T'' are jointly connected to earth through an inductance L₂ which is coupled with a coil L₃ inserted in the output circuit of a diagrammatically represented local oscillator O. Consequently by means of coil L₂ the local oscillations are supplied by means of so-called "cathode injection" to the input circuits of the triodes in such a manner that the local oscillations appear in the same phase at the control-grids of the two triodes.

A resonant circuit tuned to the intermediate

2

frequency and consisting of two inductances L_{4'} and L_{4''} and two condensers C_{4'}, C_{4''} is connected in push-pull to the anodes of the two triodes.

In series with coils L_{4'} and L_{4''} are provided high-frequency chokes L_{5'} and L_{5''} which serve to prevent a transmission of the incoming high-frequency oscillations to the receiver parts next to the mixing stage. The connecting point of coils L_{4'} and L_{4''} is connected with earth through a condenser C₅ constituting practically a short-circuit in regard to the intermediate frequency oscillations, and to the positive terminal of a source of anode potential (not represented) through a resistance R₂. Furthermore coils L_{4'} and L_{4''} are inductively coupled with a second intermediate-frequency circuit L₆, C₆, from which the output voltage of the circuit is taken. The junction of condensers C_{4'} and C_{4''} is connected to the cathodes of the two triodes in order to obtain an electric circuit having a low impedance in regard to anode currents having the oscillator frequency. Since the aforesaid circuit is particularly suitable for frequency-transformation of ultra-short waves, the input resonant circuit L_{1'}, L_{1''}, C₁ will usually be realized in the form of a Lecher system in practice.

The present circuit exhibits the drawback that the input impedance of the triodes, represented by the capacity C_{3'} and C_{3''} respectively in the drawing, notably in receiving ultra-short waves has only a small value, due to which the voltage having the oscillator-frequency and being set up between the control-grid and the cathode of any of the tubes, usually becomes too small. To supply as high as possible a voltage having the oscillator-frequency to the control-grids of the mixing triodes my copending United States Patent application No. 680,930, filed July 2, 1946,

suggests to tune the single-phase circuit constituted by the pair-wise parallel-connected impedances of the two halves of the push-pull circuit (L_{1'}, L_{1''}) and the parallel-connected input impedances of the two discharge systems (C_{3'}, C_{3''}) jointly with the impedances (L₂, C₂) common to the input circuits of the two systems, to the frequency of the local oscillations. In the present case the expression "push-pull circuit" is to be understood to mean the assembly of impedances available between two not directly interconnected input electrodes of the discharge systems, in which are flowing currents having the frequency of the incoming oscillations, the expression "input circuit of a discharge system" being understood to mean all the impedances available between the input electrodes of a dis-

55

charge system and in which are circulating currents associated with this system and having the frequency of the local oscillations associated with this system. The push-pull circuit is generally tuned to the frequency of the incoming oscillations.

The effect of the aforesaid expedient may be explained with reference to Figs. 2 and 3.

Fig. 2 represents the substitution diagram of the input circuits of the two mixing triodes. From this diagram it appears that the elements L_1' , L_1'' , C_3' , C_3'' constitute a Wheatstone bridge in regard to the local oscillations. When this bridge is in equilibrium the elements L_0 and C_1 are currentless, so that each of them can be replaced by a short-circuit. Thus ensues the substitution diagram represented in Fig. 3 where L_1 represents the parallel connection of L_1' and L_1'' , C_0 the parallel-connection of C_0' and C_0'' , C_3 the parallel-connection of C_3' and C_3'' and D the parallel-connection of the two dipole halves D' and D'' . It will now be readily appreciated that the voltage having the oscillator-frequency set up at the capacity C_3 , i. e. the voltage between the control-grid and cathode of each triode, is a maximum when series-resonance occurs in the circuit L_1 , C_2 , L_2 , C_3 . The circuit in question must consequently be tuned to the oscillator frequency. By tuning, moreover, the circuits L_1 , C_2 and L_2 , C_3 each individually to the oscillator frequency the radiation of the local oscillations can be reduced to a minimum by the antenna D . In practice the inductance of coil L_2 and the capacity of condenser C_2 may be made variable for this purpose and these elements may be adjusted in such a manner that the radiation of the local oscillations by the antenna is a minimum and the voltage having the oscillator frequency between the control grid and the cathode of each triode is a maximum.

The invention is based on the realization that the aforesaid expedient—the tuning of the said circuit to the frequency of the local oscillations—does not lead completely to the result aimed at under all conditions, and this because the said single-phase circuit is usually damped too strongly. In addition to the input damping of the mixing tubes this damping is also to be ascribed to a negative backcoupling brought about by the capacitative anode load. In fact, the capacity of condensers C_4' and C_4'' should not be chosen too high, since otherwise the impedance of the intermediate frequency circuit L_4' , L_4'' , C_4' , C_4'' , would become too low. Hence the condensers C_4' and C_4'' constitute a not negligible impedance in regard to the oscillator frequency, so that between the anode and cathode of any of the triodes an anode voltage having the oscillator frequency occurs, which leads in phase by 90° with respect to the alternating control-grid voltage. The said anode voltage involves a current through the anode control-grid capacity, which is in phase opposition in regard to the alternating control-grid voltage and consequently has a damping effect on the said circuit. It is pointed out in this respect that in a similar manner a damping is also brought about of the input resonant circuit L_1' , L_1'' , C_1 tuned to the frequency of the incoming oscillations.

The invention has for its object an improvement of the circuit according to the above-identified copending application, as a result of which the said drawbacks are avoided. According to the invention use is made of a positive backcoupling in regard to the local oscillations, as a result of

which the said single-phase circuit is undamped.

A particularly suitable embodiment of the invention is obtained by giving the positive backcoupling such a high value as to produce the local oscillations in the said circuit. In this case the distinct oscillator O can be dispensed with, which yields a great simplification of the circuit.

The back-coupling current or -voltage for the positive back-coupling is taken from a part of the output circuit in which appear both the local and the incoming oscillations, so that both the said circuit and the input circuit of the arrangement are undamped in regard to the incoming oscillations. The positive backcoupling thus obtained in regard to the incoming oscillations has the advantage that an improvement of the signal-to-noise ratio is obtained.

The damping of said circuit is generally different from the damping of the input circuit for the incoming oscillations, inter alia because the last-mentioned circuit is damped to a much higher degree by the antenna. Therefore it is advisable that the strength of the backcoupling for both kinds of oscillations should be made different, which can be ensured by taking an additional back-coupling current or voltage from a part of the output circuit in which appear either exclusively the local oscillations or exclusively the incoming oscillations.

In a suitable embodiment of the invention the positive back-coupling is obtained by making the impedance of the output circuit for the local oscillations and, if desired, also for the incoming oscillations substantially inductive. To such end, for instance, inductances may be inserted in parts of the output circuit in which appear both the local oscillations and the incoming oscillations, the desired intensity difference of the back-coupling in regard to both kinds of oscillations being obtained by inserting one or more capacities in a part of the output circuit in which appear either exclusively the local oscillations or exclusively the incoming oscillations.

The invention will be more fully explained by Figs. 4, 5 and 6 of the drawing representing embodiments thereof.

The circuit represented in Figure 4 substantially corresponds to that shown in Figure 1, but the condenser C_2 and the inductance L_2 are adjustable to permit the said circuit to be tuned to the oscillator frequency in the manner referred to above. Furthermore, according to the invention, the conductor through which the junction of the condensers C_4' and C_4'' is connected to the cathode includes an inductance L_7 . Since in the said conductor exclusively a current having the oscillator frequency is flowing a positive back-coupling in regard to the local oscillations is obtained as a result thereof. In fact, due to the voltage drop across the coil L_7 , an alternating anode voltage having the oscillator frequency and lagging the alternating control-grid voltage by 90° is set up between the anode and cathode of each of the triodes T' and T'' . Consequently currents having the oscillator frequency, which are in phase with the alternating control-grid voltage and so cause undamping of the said circuit, are passing through the anode/control-grid capacities C_7' and C_7'' . This undamping is preferably raised to such a degree that the arrangement tends to generate oscillations having the oscillator-frequency, in which case the distinct oscillator O can be dispensed with.

Figure 5 represents a circuit arrangement in which use is made at the same time of a positive

back-coupling in regard of the incoming oscillations. To this end the coil L_7 is replaced by inductances L_8' and L_8'' which inductances are inserted in a part of the output circuit in which appear both the local oscillations and the incoming oscillations. Similarly to what has been said above in regard to the local oscillations with respect to the circuit shown in Figure 4 a positive back-coupling for the incoming oscillations is now also obtained, as a result of which the input resonant circuit L_1' , L_1'' , C_1 is undamped and at the same time an increase in the signal-to-noise ratio is obtained.

The inductances of coils L_8' and L_8'' are preferably chosen in such a manner that the signal-to-noise ratio is a maximum, which necessitates as a rule a practically complete undamping of the input resonant circuit L_1' , L_1'' , C_1 . Since the input resonant circuit is comparatively strongly damped by the antenna D' , D'' , whereas the local oscillations are acted upon only to a slight degree by the antenna, the required intensity of the back-coupling in regard to the incoming oscillations is generally greater than in regard to the local oscillations, so that the back-coupling in regard to the local oscillations, which is caused by the coils L_8' and L_8'' , must be decreased. In the arrangement shown in Figure 5 this is effected by providing a condenser C_8 between the junction of the condensers C_4' and C_4'' and the cathodes of the triodes. In this case the condenser C_8 is exclusively traversed by a current having the oscillator frequency and consequently reduces the intensity of the back-coupling in regard to the local oscillations without acting on the back-coupling for the incoming oscillations.

The same effect can be obtained by connecting a condenser C_8 in parallel with the series-connection of the condensers C_4' and C_4'' . In the case of complete symmetry of the output-circuit this condenser is exclusively traversed by a current having the frequency of the incoming oscillations. To maintain the correct tuning of the circuit consisting of inductances L_4' , L_4'' and condensers C_4' , C_4'' , C_8 to the intermediate-frequency the capacities of the condensers C_4' and C_4'' , after providing the condenser C_8 , must be reduced by a corresponding amount. This results in an increase of the capacitative impedance of the output-circuit for the local oscillations, so that the intensity of the back-coupling in regard to the local oscillations falls off.

To be complete Figure 5 represents both the condenser C_8 and the condenser C_9 , but in practice one of these condensers is sufficient. By making one of the said condensers variable the intensity of the back-coupling in regard to the local oscillations can be made variable.

When it is desirable that the intensity of the backcoupling in regard to the incoming oscillations should be variable, the inductances of coils L_8' and L_8'' may, moreover, be made variable or variable condensers may be connected in series with these coils.

Figure 6 represents a circuit arrangement according to the invention, in which the input resonant circuit L_1' , L_1'' , C_1 is provided between the cathodes of the triodes T' and T'' , the grids being jointly earthed across the inductance L_2 . In this case the required reduction in intensity of the backcoupling in regard to the local oscillations can be achieved, similarly to the circuit shown in Figure 5, by providing a condenser C_8 in parallel with the series connection of con-

densers C_4' and C_4'' and by reducing the capacity of the condensers C_4' and C_4'' by a corresponding amount, or by providing an inductance L_8 between the junction of the condensers C_4' and C_4'' and the cathodes. When the back-coupling in regard to the local oscillations is to be made stronger than in regard to the incoming oscillations—this may, for instance, be the case when the local oscillations are to be generated by the arrangement itself—this can be achieved in the circuit shown in Figure 5 by replacing the condenser C_8 by an inductance or, in the circuit shown in Figure 6, by replacing the inductance L_8 by a condenser.

Instead of giving the back-coupling in regard to the incoming oscillations and in regard to the local oscillations different values, an additional damping resistance may be inserted in the input circuit for one or both kinds of oscillations. This damping resistance may, for instance, be provided in parallel with the condenser C_1 when an additional damping for the incoming oscillations is necessary. When, in contradistinction thereto, an additional damping for the local oscillations is required, a damping resistance in series with the condenser C_2 or with the inductance L_2 may be provided for this purpose.

What I claim is:

1. An arrangement for mixing an incoming wave with local oscillations to produce an intermediate frequency signal, comprising a pair of electron discharge tubes each having a cathode electrode, a grid electrode and an anode, a first resonant circuit arranged to apply the incoming wave in push-pull relation to one set of corresponding electrodes in said tubes, an output system including a second resonant circuit coupled to the anodes of said tubes to derive in push-pull relation the intermediate frequency signal therefrom, a third and series resonant circuit coupled between the electrical midpoint of said first circuit and the other set of corresponding electrodes to apply local oscillations in cophasal relation to the grid electrodes of said tubes, and means to introduce positive backcoupling between the output system of said tubes and said third resonant circuit.

2. A mixing circuit as defined in claim 1 further characterized in that said means has a value at which the intensity of said positive backcoupling generates local oscillations in said mixing circuit.

3. An arrangement for mixing an incoming wave with local oscillations to produce an intermediate frequency signal, comprising a pair of electron discharge tubes each having a cathode, a grid and an anode, a first resonant circuit arranged to apply the incoming wave in push-pull relation to the grids of said tubes, a second resonant circuit coupled to the anodes of said tubes to derive in push-pull relation the intermediate frequency signal therefrom, a third and series resonant circuit coupled between the electrical midpoint of said first circuit and the cathodes of said tubes to apply local oscillations in cophasal relation to the grids of said tubes, and means to effect negative damping of said first and third resonant circuits, said means including an inductive impedance interposed between each of said anodes and said second resonant circuit to introduce positive backcoupling between the anode-cathode circuits of said tubes and said first and third resonant circuits.

4. An arrangement for mixing an incoming wave with local oscillations to produce an inter-

mediate frequency signal, comprising a pair of electron discharge tubes each having a cathode, a grid and an anode, a first resonant circuit arranged to apply the incoming wave in push-pull relation to the grids of said tubes, a second resonant circuit coupled to the anodes of said tubes to derive in push-pull relation the intermediate frequency signal therefrom, a third and series resonant circuit coupled between the electrical midpoint of said first circuit and the cathodes of said tubes to apply local oscillations in cophasal relation to the grids of said tubes said second circuit including, a pair of condensers connected in series between said anodes, and an inductive impedance connected between the junction of said condensers and the cathodes of said tubes for providing positive backcoupling to effect negative damping of said third resonant circuit.

5. An arrangement for mixing an incoming radio wave with local oscillations to produce an intermediate frequency signal comprising a pair of electron discharge tubes each having a cathode, a grid and an anode, a first parallel-resonant circuit including a center tapped inductance connected between said grids, said first circuit being tuned to the incoming wave to apply same in push-pull relation to said grids, a second parallel-resonant circuit constituted by an inductor in parallel with a pair of series connected condensers connected between the anodes of said tubes and tuned to the intermediate frequency, radio frequency chokes interposed between the ends of said inductor and said condensers, a series-resonant circuit connected between the tap in said inductance and the cathodes of said tubes and tuned to the frequency of local oscillations to apply same in cophasal relation to said grids, inductive feedback impedances interposed between each anode and each choke to effect negative damping of said first parallel-resonant circuit and said series-resonant circuit, and an additional inductive feedback impedance connected between the junction of said series-connected condensers and the grids of said tubes to increase the negative damping of said series resonant circuit to the point resulting in the generation of local oscillations.

6. An arrangement for mixing an incoming radio wave with local oscillations to produce an
